UNITED STATES PATENT OFFICE.

FREDERICK D. SEARS AND AXEL O. SODERGREN, OF MINNEAPOLIS, MINNESOTA.

PORTABLE PICTURE-GALLERY.

1,082,914.

Specification of Letters Patent. Patented Dec. 30, 1913.

Application filed August 26, 1912. Serial No. 716,972.

To all whom it may concern:

Be it known that we, FREDERICK D. SEARS and AXEL O. SODERGREN, citizens of the United States, residing at Minneapolis, in the county of Hennepin and State of Minnesota, have invented certain new and useful Improvements in Portable Picture-Galleries; and we do hereby declare the following to be a full, clear, and exact description of the invention, such as will enable others skilled in the art to which it appertains to make and use the same.

Our invention has for its object to provide a simple and efficient portable moving picture gallery and to such ends, generally stated, the invention consists of the novel devices and combinations of devices herein-after described and defined in the claims.

More particularly, as stated, our invention comprises a gallery or compartment from which external light is cut off, having an internal screen onto which the picture is projected, and the gallery or casing having a plurality of peek-holes through which the projected picture on the screen may be seen by persons standing outside of the casing.

This improved gallery or apparatus, in what we at present believe to be its preferred form, is illustrated in the accompanying drawings wherein like characters indicate like parts throughout the several views.

Referring to the drawings, Figure 1 is a view partly in side elevation and partly in vertical section, showing the complete portable and extensible gallery; Fig. 2 is an end elevation of the gallery looking at the same from the right toward the left in respect to Fig. 1; Fig. 3 is a section taken on the line $x^3 x^3$ of Fig. 1; Fig. 4 is a transverse vertical section taken on the line $x^4 x^4$ of Fig. 1; Fig. 5 is a fragmentary view in horizontal section on the line $x^5 x^5$ of Fig. 2; and Fig. 6 is an elevation of the parts shown in Fig. 5 and Fig. 7 and is a fragmentary view in section on the line $x^7 x^7$ of Fig. 4.

The gallery illustrated is a double ended structure in which the pictures on the screen may be viewed from both ends of the casing or from both sides of the screen and it comprises main body sections 1, and extensible sections 2, 3 and 4, which sections in the order indicated are made successively smaller in diameter and are arranged to telescope one into the other. The screen 5

is of a translucent material such as thin canvas or muslin, and at its outer edge it is hemmed around a radially expansible spring ring or frame 6. The ring 6 is situated in the plurality of retaining forks 7, having threaded stems projecting outward through one of the main case sections 1 and secured thereto by nuts 8. The two main case sections 1 are preferably detachably connected, this being accomplished by means of flanged hoops 9, secured to the abutting edges of said case sections 1 and bolted or otherwise rigidly but detachably connected. The said body sections 1 are shown as supported by suitable framework 10 and the vertical legs 7 of which are passed through lugs 11 on supporting yokes 11, the legs being secured thereto by set screws 12, that permit vertical adjustments of the said yokes 11, and hence, of the entire gallery. The case sections 2, 3 and 4, when extended, are supported from the main case sections 1 by chains or cables 13.

One of the outer and smaller of the case sections 4 is provided with axially located light passages or perforations 14, and the housing 15, of the moving picture machine is secured to this case section 4 in position to project the picture rays through the adjacent passage 14 and onto the screen 5, as indicated by the radiating dotted lines marked Y on Fig. 1. The chain or cable 16 also connects the housing 15 to one of the main case sections 1 and assists in supporting the same in proper working position.

The several sections of the casing, except the section 4 to which the picture apparatus is connected, are formed each with a plurality of peek-holes 17, in their annular vertical outer end faces (see Fig. 2). Preferably, each peek-hole 17 is normally closed by a vertically movable shutter 18, having a perforation 19, as adapted to register with the peek-hole 17 when the said shutter is held in a raised position.

The picture projected on the translucent screen 5, will be visible on both sides thereof and hence, may be simultaneously viewed by a large number of people, to-wit, as many people as there are peek-holes looking onto the gallery from both ends of the casing sections, or from both sides of the screen.

In Fig. 3, the numeral 20 indicates a peek-hole for the operator, located in the end of the small case section 4, to which the picture

machine is attached. This peek-hole 20, as shown, is provided with normally closed shutter 21.

When it is desired to move the gallery or apparatus from place to place, the sections 5 1, 2, 3 and 4 may be telescoped together; and whenever the apparatus must be passed through a narrow passage, such as a doorway, which is wider than the length of the 10 two body sections 1, the said sections 1 may be separated. It is thought that friction will overcome the horizontal thrust of the chains 13 and 16 and thereby prevent the telescoping of the sections 1, 2, 3 and 4, but 15 if, in actual practice, such is not the case, suitable locking means may be provided to prevent the telescoping of said sections.

What we claim is,

1. The combination with a gallery or 20 enclosure and a screen therein, of means for projecting a picture onto said screen, said gallery having peek holes through which the picture on said screen may be viewed by persons on the exterior of said gallery, 25 the said gallery being collapsible and having means for holding it extended.

2. The combination of a gallery or 30 enclosure and a screen therein, of means for projecting a picture onto said screen, said gallery having peek-holes through which the picture on said screen may be viewed by persons on the exterior of said gallery, 35 said gallery being made up of an extensible and contractible casing.

3. The combination of a gallery made up 40 of extensible sections of varying diameter, with a screen applied on the larger section of said gallery, and a picture machine applied to the smaller section of said gallery, and arranged to project pictures into said gallery and onto said screen, said gallery having peek-holes in its extensible sections, 45 through which pictures on said screen may be viewed from the exterior of said gallery.

4. The combination of a gallery or 50 enclosure and a screen therein, of means for projecting a picture onto said screen, said gallery having peek-holes through which the picture on said screen may be viewed by persons on the exterior of said gallery, and the said peek-holes having automatically closed shutters.

5. The combination with a gallery made 5 up with telescopically connected sections of 10 materially different diameter, of a screen applied in the larger section of said gallery, and a picture apparatus associated with the

smaller section of said gallery and arranged to project pictures into said gallery and onto said screen, the sections of said gallery in 60 their outer end portions, having peek-holes, through which the picture on said screen may be viewed by persons at the exterior of said gallery.

6. The combination of the gallery made 65 up of a relatively large intermediate section and extensible sections of decreasing diameter, adapted to be projected from both ends thereof, of a translucent screen in the said main section, and a picture apparatus associated with the smaller section at one end of said gallery, arranged to project pictures into said gallery and onto said screen, the sections of said gallery on both sides of said screen having peek-holes through which the 70 picture on both sides of said screen may be viewed by persons on the outside of said gallery.

7. The combination of a gallery made up 75 of a relatively large intermediate section and extensible sections of decreasing diameter, adapted to be projected from both ends thereof, of a translucent screen in the said main section, and a picture apparatus associated with the smaller section at one end 80 of said gallery, arranged to project pictures into said gallery and onto said screen, the sections of said gallery on both sides of said screen having peek-holes through which the picture on both sides of said screen may be 85 viewed by persons on the outside of said gallery, and the said main section of said gallery being separably connected approximately at its central portion.

8. The combination with a gallery and a 90 screen therein, the casing of said gallery being formed by approximately cylindrical sections decreasing successively in diameter in a common direction, and the said sections in their ends having peek holes through 95 which pictures on the screen may be viewed from the exterior of the gallery, and a picture apparatus associated with the smaller section of the said gallery and arranged to project pictures into said gallery and onto 100 said screen.

In testimony whereof we affix our signatures in presence of two witnesses.

FREDERICK D. SEARS.
AXEL O. SODERGREN.
